UNITED STATES PATENT OFFICE.

BENJAMIN E. GETZ, OF MORTON, ILLINOIS, ASSIGNOR, BY MESNE ASSIGNMENTS, OF ONE-HALF TO GETZ POWER WASHER CO., OF MORTON, ILLINOIS, A CORPORATION OF ILLINOIS, AND ONE-HALF TO WESTINGHOUSE ELECTRIC & MANUFACTURING COMPANY, OF EAST PITTSBURGH, PENNSYLVANIA, A CORPORATION OF PENNSYLVANIA.

WASHING MACHINE.

Application filed April 14, 1923. Serial No. 631,971.

This invention has reference to washing machines, and particularly to that type including a clothes container or tub which is mounted for movement in the frame of the machine. In its preferred form the container or tub is oscillated, but to those skilled in this art it will be understood that the movement of the operating means could be extended so as to impart an alternating rotary movement to the container or tub, so as to rotate it approximately a full revolution before reversing its operation, instead of a partial rotation, as herein shown.

The invention has for its principal object to provide a controllable means for the tub moving means; such controllable means movable to different positions and adapted in one of its positions to impart movement to the tub and in another of its positions adapted to restore the tub to normal stopped position, without stopping the movement of the tub moving means.

The invention herein described and shown is an improvement on the generic idea disclosed in the application of Thomas Littwiller and John Leader bearing Serial No. 442,336 and as to such generic disclosure a disclaimer is here made. Furthermore, this application is a companion to applications filed of even date herewith bearing Serial Nos. 631,966, 631,967 and 631,968. In said applications bearing Serial Nos. 631,967 and 631,968, the mechanism is shown applied to an "oscillatory" tub, or one which makes less than one complete revolution during each oscillation, and in said application bearing Serial No. 631,966 the mechanism is shown applied to an "alternating rotary" tub, or one which makes at least one complete revolution during each oscillatory movement.

The present improvement resides in the controllable means which is of a walking-beam type, and includes a lever having an adjustable fulcrum adapted to alternately place the mechanism in operative relation with the power means to impart movement to the tub, and in neutral relation with the power means to restore the tub to normal position and stopped, without stopping the movement of the operating means; such lever having connection with the operating means and also the tub.

That the invention may be more fully understood, reference is had to the accompanying drawings, forming part of the description, and illustrating a preferred embodiment of the invention, in which:—

Figure 1 is a side elevation of my controllable means for washing machines, the tub being shown in dotted lines in different positions, the full line position of the mechanism being the operative position and the dotted line positions of such mechanism showing how movement is imparted to the tub;

Figure 2 is a view similar to Figure 1, except that the frame is omitted and the mechanism is shown in full lines in neutral position and the lever having the adjustable fulcrum idling and without imparting movement to the tub, and

Figure 3 is a detail in plan of a part of the lever having the adjustable fulcrum.

Like characters of reference denote corresponding parts throughout the figures.

The frame structure which may be of any suitable character, is shown in outline, in dotted lines; likewise the clothes container or tub, which may be of any suitable design. Full lines are employed to show the tub moving means and controllable means, certain positions of which, however, are illustrated by dotted lines.

The frame of the machine includes a base member 1, side members 2 and a top or cover 3. Such frame, if desired, like many present day machines may also have a cabinet or enclosing casing, not shown. The frame structure is not extended to show a supporting means for the container or tub 4, but it is understood a suitable bearing support for trunnions 5 or other journal means of the tub would be provided. In the present disclosure, the movement of the container or tub is preferably an oscillatory movement. The container or tub would naturally include an opening not shown, through which clothing or other materials would be inserted into and withdrawn therefrom, and such opening covered or closed, when desired by a suitable lid or cover, not shown.

Figure 1 shows the container or tub in different dotted positions. In the position "A", being the normal position of the tub when the controllable means is in the full

line position shown in Figure 2, said container or tub has been restored to its normal position, or as some would say returned to its neutral position and stopped, the operating means continuing in operation, and the controllable means idling and without movement being imparted to the container or tub. Also, in Figure 1 the positions "B" of the container or tub show it oscillating, being the result which is obtained by adjusting the controllable means to the position shown in said figure.

By "normal" or "neutral" position of the tub, it is to be understood that that is the position the tub occupies when it is stopped so that the lid or cover thereof may be removed by an attendant to permit the removal of clothes or fabrics from the tub and the placing of other articles or materials therein. Also, by the use of the word "restore" I mean the bringing back or righting of the tub to "normal" or "neutral" position at the same time that the operating means is made ineffective so far as operating the tub is concerned, yet without disturbing the movement of the operating means.

By the use of a mechanism such as I employ and which I am about to describe, the use of spring constraining means for returning the tub to its normal position and for balancing the tub, are unnecessary and entirely done away with, and yet the attendant need have no concern about the tub being restored to normal position, as such is the natural result when the controllable means is moved to discontinue the movement of the tub.

7 designates a driving shaft, which may form a part of or be included in any suitable transmission, not shown, through which power is imparted to said shaft from the usual motor, not shown. To one end of said shaft is connected a crank-arm 8.

Connected to the container or tub 4, preferably through a trunnion 5, or similar member, is a crank-arm 9 to which is pivotally connected, at 9^a, the depending bar 10 which has a pivotal connection at its lower end with a pivot-member 11 connected with an ear 12 on one end of a lever 13; said ear being preferably in parallel relation with and spaced from the body of the lever, see Figures 1 and 3. The lever, for a portion of its length is provided with a longitudinally disposed guide-way or slot 14 in which is slidably adjustable a pivot-member 15 forming the fulcrum for said lever 13. Said member 15 has two extreme and predetermined positions of adjustment, being those positions shown in full lines in Figures 1 and 2, the latter position placing the pivot-member 15 in axial coincidence with the pivot-member 11 connected to the ear 12 of said lever. The pivot-member 15 being un-

der the control of an attendant, it will be understood that if held at any point between its two extreme and predetermined positions that a variable movement may be imparted to said tub.

The lever 13 at the end opposite to that having the ear 12 has connected thereto a roller 16 movable in arc-shaped guide 17 supported on the frame of the machine, and connected with this end of the lever 13 is a preferably depending connecting bar 18 having a pivotal connection at its lower end with a bell-crank lever 19, to which is also connected a reach bar 20 in operative connection with the crank-arm 8.

A control lever is provided, designated 21, which is pivotally connected at its lower end to a suitable frame part and extends to the top of the machine in easy and convenient reach of an attendant. Said lever, as shown, has connection with the pivot-member 15, whereby, as the lever is moved said pivot-member 15 may be adjusted in the slot 14 of the lever 13 and by such adjustment change the fulcrum point of the lever 13. When the member 15 is in the position shown in Figure 1 the opposite ends of said lever 13 may be moved to substantially equal distances on either side of a line passing longitudinally through the lever, or to the position shown in dotted lines, in said figure, and as a result impart reciprocal movement to the bar 10 and oscillate the crank 9 to impart similar oscillatory movement to the tub 4. On the other hand when the member 15 has been moved to the position shown in Figure 2, in axial spaced relation with the member 11, then this becomes the fulcrum point on which the lever 13 may be swung, and owing to the two pivotal points 11 and 15 being in axial coincidence it will be observed that as the lever 13 is oscillated there can be no movement imparted to the bar 10, or the crank 9, or the tub 4; the lever 13 idling up and down on the pivot-member 15 somewhat in the manner shown by the dotted lines in Figure 2, no movement being imparted to the tub and without in any way interfering with the operation of the operating means.

It will be understood that the pivot-member 15 may be moved by a quick throw of the lever 21, or more slowly by a gradual movement of said lever. By a very slow movement of said lever 21 a gradual and variable oscillation will be imparted to the tub, either when starting or stopping the same, it being apparent that moving the member 15 to neutral position, see Figure 2, will automatically and simultaneously restore the tub to normal position and stop it.

It will be further understood, that if the lever 21 is moved less than a full stroke, that less than a full oscillation of the tub may

be obtained. This is desirable in the handling of coarse and fine fabrics and clothing. Therefore, it is possible to obtain a variable movement of the tub, depending on 5 the movement imparted to the lever 21 and the pivot-member 15, and to bring the tub to a stop without jerking and jiggling.

What I claim is:—

1. In a machine of the character described, in combination with a tub mounted for movement, an operating means, means connecting said operating means with said tub, including a slotted lever, guiding means for one end of said lever, an operator's lever, 10 and means connecting said operator's lever with said slotted lever and slideable in said slot, whereby the fulcrum point of said slotted lever may be changed, and thereby

place said slotted lever alternately in neutral and tub operative position. 20

2. In a machine of the character described, in combination with a tub mounted for movement, an operating means, a slotted lever having a changeable fulcrum point, whereby said lever may be alternately placed 25 in neutral and tub operating positions, a guide for one end of said lever, connections between the opposite end of said lever and said tub, connections between said operating means and the guided end of said 30 slotted lever, and a hand lever for changing the fulcrum point of said slotted lever.

In witness whereof I have hereunto affixed my hand and seal this 11th day of April, 1923.

BENJAMIN E. GETZ.
